CLAIM

The ornamental design for a safety blood collection assembly, as shown and described.

DESCRIPTION

FIG. 1 is a perspective view of a safety blood collection assembly having an exposed needle, and with the needle shield removed, in accordance with an embodiment of the present invention;

FIG. 2 is a top view of the safety blood collection assembly of FIG. 1;

FIG. 3 is a left side view of the safety blood collection assembly of FIG. 1;

FIG. 4 is a front view of the safety blood collection assembly of FIG. 1;

FIG. 5 is a rear view of the safety blood collection assembly of FIG. 1;

FIG. 6 is right side view of the safety blood collection assembly of FIG. 1;

FIG. 7 is a bottom view of the safety blood collection assembly of FIG. 1;

FIG. 8 is a perspective view of the safety blood collection assembly of FIG. 1 having a needle shield disposed thereon in accordance with an embodiment of the present invention;

FIG. 9 is a top view of the safety blood collection assembly of FIG. 8;

FIG. 10 is a left side view of the safety blood collection assembly of FIG. 8;

FIG. 11 is a front view of the safety blood collection assembly of FIG. 8;

FIG. 12 is a rear view of the safety blood collection assembly of FIG. 8;

FIG. 13 is a right side view of the safety blood collection assembly of FIG. 8; and,

FIG. 14 is a bottom view of the safety blood collection assembly of FIG. 8.

The portions of the safety blood collection assembly shown in broken lines in FIGS. 5, 11, and 12 form no part of the claimed design.
